UNITED STATES PATENT OFFICE.

SCOTT H. PERKY, OF KEESEVILLE, NEW YORK.

DESIGN FOR A SOUP STICK.

Application filed May 3, 1921. Serial No. 466,616. Term of patent 14 years.

To all whom it may concern:

Be it known that I, SCOTT H. PERKY, a citizen of the United States, residing at Keeseville, in the county of Essex and State of New York, have invented a new, original, and ornamental Design for a Soup Stick, of which the following is a specification, reference being had to the accompanying drawing, forming part thereof.

The figure is a perspective view showing my new design for a soup stick. The right end of the soup stick is of the same design as that shown for the left end.

I claim:—

The ornamental design for a soup stick, as shown and described.

SCOTT H. PERKY.
